UNITED STATES PATENT OFFICE.

ALBERT EDWIN HALE, OF TUCSON, ARIZONA.

HEADLIGHT.

1,244,200.

Specification of Letters Patent. Patented Oct. 23, 1917.

Application filed January 4, 1917. Serial No. 140,555.

To all whom it may concern:

Be it known that I, ALBERT E. HALE, a citizen of the United States, and a resident of Tucson, in the county of Pima and State of Arizona, have invented a new and Improved Headlight, of which the following is a full, clear, and exact description.

My invention relates to headlights for vehicles and is particularly suitable for motor vehicles.

An object of the invention is to provide a simple and inexpensive headlight in which the rays normally directed out of the reflector above the central plane thereof are collected by a secondary reflector within the main reflector to concentrate the central portion of the beam of light issued by the headlight.

With the above and other objects in view, the nature of which will more fully appear as the description proceeds, the invention consists in the novel construction, combination and arrangement of parts as herein fully described, illustrated and claimed.

In the accompanying drawing, the figure is a longitudinal section of a headlight embodying my invention.

Referring to the drawing, 4 is the lamp casing, which is in the shape of a hollow paraboloid, the interior surface 5 of which forms the reflector of the light. A source of light 6 is located in the focus of the reflecting surface.

To concentrate the illumination in the central part of the headlight, I have introduced

a secondary parabolic reflector 7, which is a truncated dome through which the source of light enters the said secondary reflector. The secondary reflector is coaxial with the first and is supported at the rear end 40 of the primary reflector by a bracket 8 which may be secured either to the lamp socket as shown, or to the reflector, if so desired. The secondary reflector is so secured that its focus substantially coincides 45 with the focus of the primary reflector. In consequence of that arrangement any rays falling upon the secondary reflector will be directed parallelly to the axis of the headlight and, therefore, concentrate the 50 central beam, which is the desired point of concentration.

The secondary reflector is so truncated that it will only receive the rays from the source of light which would not fall upon 55 the primary reflector 4.

I claim:

In a headlight of the class described, a primary parabolic reflector, a source of light in the focus thereof, a secondary parabolic reflector coaxial with the first, said secondary reflector having the dome portion about the focus cut away to admit the source of light, and means for supporting the said secondary parabolic reflector within the first so that the secondary reflector will receive only the rays from the source of light which would otherwise fall outside of the primary reflector.

ALBERT EDWIN HALE.
